UNITED STATES PATENT OFFICE.

BENJAMIN H. FREEDMAN, OF NEW YORK, N. Y.

TRousERS-SUPPORTER.

1,243,828.

Specification of Letters Patent. Patented Oct. 23, 1917.

Application filed May 21, 1917. Serial No. 169,828.

To all whom it may concern:

Be it known that I, BENJAMIN H. FREEDMAN, a citizen of the United States, and a resident of the city, county, and State of New York, have invented a certain new and useful Improvement in Trouser-Supporters, of which the following is a specification.

The invention relates to trouser supporters and has for its object the production of an article of this character which shall support the trousers properly from the shoulders without the use of suspenders or belt.

This object is accomplished by attaching the trouser supporting means to a vest or other garment in a new and novel manner whereby the strain of supporting the trouser is evenly distributed over the vest.

With this and other objects in view, I have devised the combination of parts hereinafter disclosed and finally pointed out in the claims appended hereto.

Referring to the accompanying drawing forming part hereof:

Figure 1 is a front elevation of a vest, to which my improved trouser supporters are secured, the vest being spread open to reveal the same,

Fig. 2 is a perspective view illustrating the device in use, with one of the front flaps of the vest in an open position,

Fig. 3 is a view of one of the trouser supports indicating the manner in which it is secured to the vest, and,

Fig. 4 is a sectional view on the line 4—4 of Fig. 3 looking in the direction of the arrows.

Throughout the various views of the drawings similar reference characters designate similar parts.

In the preferred embodiment of my invention disclosed in the accompanying drawing, 1 indicates a vest of the ordinary type having a lining 2, the usual outer material 3, front flaps 4 and the rear adjusting straps 5.

The trousers supporting means are secured to the inner side of the front flaps 4 and each of the supports has a strip 6 of any desired material such as the material from which the vest is made. This strip 6 is preferably inelastic, although if desired it may be formed of an elastic material. This strip 6 is secured to the garment by the stitches 7 which extend longitudinally of the strip and pass through the lining 2 and outer material 3 of the vest. In order

that these stitches 7 are not discernible on the exterior of the garment, the strip 6 is so positioned that these stitches fall within the area of the pocket 11. It will therefore be seen that the flap 11 forming the pocket of the garment covers the stitches 7 or other means which may be adapted to secure the strip 6 in position.

Secured to the strip 6 in spaced-apart relationship and depending therefrom is a pair of supporting straps 8. These straps are preferably of an elastic material and their length may be adjusted as desired by the adjusting buckles 9. Depending from the lower ends of these straps are loops 10 which engage the usual suspender buttons 12 on the trousers to support the trousers in a manner readily understood.

From the foregoing the operation of my improved trouser supporters will be readily understood. These supporters hold the trousers firmly from the shoulders of the wearer without discomfort or inconvenience. The substantially great width of the supporting strip 6 and the spaced-apart relationship of the straps 8 depending therefrom distributes the strain of supporting the trousers over considerable area whereby a distortion of the garment is avoided. The placing of the strip 6 within the area defined by the pocket is of importance inasmuch as it renders the supporters and the means for attaching them, such as the stitches 7, indiscernible from the exterior of the vest. For instance when buckles 9 or other adjusting means are used on the strap 8 they cause a bulging or unsightly protrusion of the material of the vest. However, when the supporter is placed within the area defined by the pocket these bulges are covered by the flap 11 of the pocket, so that the vest at all times presents a smooth and perfect fitting appearance.

From the foregoing it is obvious that my invention is not to be restricted to the exact embodiment herein shown but is broad enough to cover all structures coming within the scope of the annexed claims.

What I claim is:

1. A device of the class described comprising a garment, and trouser supporting means secured on the inner side of the garment with its means of attachment to the garment placed within the area defined by a pocket in the garment.

2. A device of the class described com-

prising a garment, a pocket formed therein, a trouser support secured on the inner side of said garment having a transversely extending elongated strip, with supporting straps depending therefrom, said strip being secured to the garment within the area defined by a pocket in the garment.

3. A device of the class described comprising a garment, a pocket formed therein, 10 a transversely extending strip of material attached to the inner side of the garment, the means of attachment of said strip to the garment being concealed by the pocket, and spaced-apart downwardly depending supporting straps secured to said strip.

4. A device of the class described comprising a vest or other garment having a lining, outer material and a pocket, a transversely extending strip of material secured to the 20 lining and outer material and behind the pocket and downwardly depending spaced-apart supporting straps secured to the strip.

5. A device of the class described comprising a vest or other garment having a lining, outer material and a pocket, an elongated 25 transversely extending strip of material stitched to the lining and outer material, the securing stitches being concealed by the pocket and a pair of spaced-apart downwardly depending supporting straps secured to the strip.

6. A device of the class described comprising a vest or other garment having a lining, outer material and a pocket, an elongated 30 strip of material extending transversely of the garment and secured thereto by stitches extending longitudinally of the strip and passing through the lining and outer material, said securing stitches being concealed from exterior view by the pocket, and a pair 35 of adjustable, downwardly depending trouser supporting straps secured to the lower longitudinal side of the strip.

Signed at the city, county and State of New York, this 17th day of May, 1917.

BENJAMIN H. FREEDMAN.
